SLICING MACHINE

Jetze van Hoorn, Voorburg, Netherlands, assignor to U. S. Slicing Machine Company, La Porte, Ind., a corporation of Indiana

Application December 19, 1928, Serial No. 327,001, and in Great Britain May 14, 1928

16 Claims. (Cl. 146—94)

This invention relates to slicing machines and an object of the invention resides in a novel manner of associating a slice receiver with the reciprocating table of the machine so that the receiver will reciprocate with the table when the driving mechanism of the machine is operated.

Other objects will appear as the description proceeds.

In the drawings:—

10 Fig. 1 is an elevation of a slicing machine showing the association of the slice receiver therewith;

Fig. 2 is a section taken on the line 2—2 of Fig. 1;

15 Fig. 3 is an elevation of a slice receiver adapted for a modified form of the invention;

Fig. 4 is an elevation of a slicing machine having connected therewith the receiver shown in Fig. 3.

20 Fig. 5 is a cross-section on line 5—5 of Fig. 4.

The numeral 10 designates the base of the slicing machine supporting the horizontal guides 11 and 12 upon which the work table 13 is mounted for reciprocation past the slicing knife 14.

25 A feed plate or material support 15 slidably transversely of the table 13 supports the material 15' to be sliced and is fed toward the slicing knife by feed mechanism well known in the art.

The table 13 is reciprocated by the usual 30 mechanism comprising a crank 16 and connecting rod 17 driven by a shaft 18 to which a hand wheel 19 is connected.

A shaft 21 (Fig. 1) is rotated by the drive shaft 18 through gearing not shown, to rotate a shaft 35 21 and sprocket wheel 20. A sprocket 23 rigid with a shaft 22 is driven by the sprocket 20 through a chain 25 and a second sprocket 24 rigid with the shaft 22 drives a sprocket 26 rigid with the knife shaft 27 by means of a chain 28.

40 An arm or bracket 28' secured to the table 13 by means of screws 29 extends downwardly from the table 13 and is rigidly secured to a slice receiver 30 positioned on the side of the knife 14 opposite the table 13.

45 A ledge 31 is secured to the base 10 by means of bolts 32. The receiver 30 is provided with bearings 35 within which are journaled rollers 34 adapted to ride along tracks 33 mounted on the ledge 31. The receiver 30 has an inclined

50 receiving surface 36 sloping upwardly and away from the plane of the knife 14 and may be provided with a projecting portion 37 at one end (Fig. 1) to serve as an abutment for the slices.

Owing to the fact that the receiver 30 moves 55 in unison with the table 13, there is no relative

motion between the substance to be sliced and the surface upon which the slice is received. The slices are therefore deposited one upon the other in an orderly stack and are not crumpled due to the relative motion between the parts as 60 is the case when a stationary receiver is used.

In Fig. 4, there is illustrated an arrangement wherein the slice receiver 30' is reciprocated with the table but at a speed slightly greater than the speed of the table. This additional speed of the 65

receiver is sometimes desirable because it has the effect of stretching the slices causing them to lie more nearly flat than when the receiver and table move at the same speed. In the form shown in Fig. 4, the table 13 is reciprocated on the 70

guides 11 and 12 by the hand wheel 19, crank 16 and connecting rod 17 (the latter two parts not being shown in Fig. 4) in the same manner as in the first form of the invention. The driving

connection to the knife 14 and to the receiver 75 30' is, however, somewhat different. The table 13 is provided with rack teeth 40 meshing with a pinion 38 rigid with a larger sprocket 39. A chain 41 connects the sprocket 39 with a sprocket

52 rotatable on a shaft 40' and the knife is driven from a second sprocket 50 rigidly secured to the shaft 40' by means of a chain 42. A chain 43 passing over a sprocket 44 is disposed

parallel with the table 13 and is driven by a third sprocket 51 rotatable on the shaft 40, but rigid 80 with sprocket 52. Thus the chains 41 and 43 are reciprocated by the table while the chain 42 moves continuously in one direction. The receiver 30' differs from the form shown in Fig. 1

85 only in that it is provided with elements 45 for connection with the chain 43.

When the hand wheel 19 is turned the receiver 30' is driven at a slightly greater speed than the table 13 through the gearing 40, 38, 39 and the sprocket on the shaft 40'. 95

Obviously those skilled in the art may make various changes in the details and arrangements of parts without departing from the spirit and scope of the invention as defined by the claims hereto appended, and I therefore do not wish to 100 be restricted to the precise construction herein disclosed.

I claim:—

1. In combination with a slicing machine having a vertically disposed slicing knife and a 105 horizontal work table mounted for reciprocation at one side of said knife, a ledge mounted below said table extending laterally beyond the edge thereof, a slice receiver mounted for movement on said ledge parallel to said table, driving mech-

anism, and connecting means between said receiver, table and mechanism to reciprocate said table and receiver together.

2. In combination with a slicing machine having a vertically disposed slicing knife and a work table mounted for reciprocation at one side of said knife, a ledge mounted below said table extending laterally beyond the edge thereof, a slice receiver mounted for movement on said ledge 10 parallel to said table, an arm rigidly connecting said receiver with said table, and driving mechanism for reciprocating said receiver.

3. In combination with a slicing machine having a slicing knife and a work table mounted for reciprocation at one side of said knife, of a slice receiver at the opposite side of said knife, mechanism for reciprocating said table, and means connecting said receiver with said mechanism for reciprocating said receiver with said table in a 20 path parallel thereto and at a speed greater than the speed of said table.

4. In combination with a slicing machine having a vertically disposed slicing knife and a horizontal work table mounted for reciprocation 25 at one side of said knife, a slice receiver at the opposite side of said knife having a receiving surface below the surface of said table, mechanism for reciprocating said table, and means connecting said receiver with said mechanism for reciprocating said receiver with said table in a 30 path parallel thereto and at a speed greater than the speed of said table.

5. In combination with a slicing machine having a vertically disposed slicing knife and a horizontal work table mounted for reciprocation at 35 one side of said knife, of rack teeth carried by said table, a pinion driven by said teeth, a chain driven by said pinion parallel to said table and at a speed greater than the speed of said table, 40 and a slice receiver connected with said chain to move therewith.

6. In a slicing machine the combination with a slicing knife and a work table mounted for reciprocation at one side of said knife, of a slice receiver arranged on the opposite side of said 45 knife, mechanism for reciprocating said table, and means for moving said receiver in a path parallel to the path of movement of said table but at a speed greater than the speed of said 50 table.

7. A slicing machine comprising a slicing knife, a substance support, and a slice receiver movable past said knife in a path substantially parallel to the cutting plane of said knife and at a 55 speed greater than the speed with which said table is moved past said knife.

8. A slicing machine comprising a movable table, a receiver movable in a substantially rectilinear path, a slicing knife, and driving means between said table and said receiver for driving the one by the other, comprising change speed gearing for driving said receiver at a speed greater than the rate of speed of said table.

9. A slicing machine comprising a slicing 65 knife, means for driving said slicing knife, a substance supporting carriage, means for driving said carriage past the cutting edge of said knife, a slice receiver adapted to receive slices from the knife as they are cut thereby, a chain 70 operatively connected to said receiver, and a second chain driven by said table as it reciprocates for driving said first mentioned chain at a different rate of speed than said carriage.

10. A slicing machine comprising a rotating 75 knife, a carriage movable past the cutting edge

of said knife on one side thereof, a slice receiver adapted to reciprocate on the other side of said slicing knife, means for driving said table, a reciprocating chain driven by said table as said table reciprocates, and means for connecting said reciprocating chain to said receiver to cause said receiver to move past the cutting edge of said knife on the side of said knife opposite that on which said table is arranged, said chain being driven at a different rate of speed than said carriage.

11. A slicing machine comprising a rotating knife, a carriage movable past the cutting edge 80 of said knife on one side thereof, a slice receiver adapted to reciprocate on the other side of said slicing knife, means for driving said table, a reciprocating chain driven by said table as said table reciprocates, and means for connecting said reciprocating chain to said receiver to cause said receiver to move past the cutting edge of said knife on the side of said 85 knife opposite that on which said table is arranged and at a speed greater than the speed of movement of said reciprocating table.

12. A slicing machine comprising a slicing 90 knife, a reciprocating table on one side of the cutting plane of said knife, a slice receiver adapted to reciprocate in a path parallel to the cutting plane of said knife for receiving slices as the same are cut from a substance by said 95 knife, said slice receiver being substantially flat and having its supporting surface stationary with respect thereto and extending upwardly and outwardly away from the cutting plane of said knife, an abutment arranged substantially perpendicular to the path of reciprocation of said receiver for preventing movement of the slices off said receiver, and a deflector for deflecting slices broad side down onto said supporting surface.

13. A slicing machine comprising a slicing 100 knife, a substance supporting carriage movable past the cutting edge of said knife, a receiving member adapted to move parallel to the cutting plane of said knife and receive slices as they are 105 cut by said knife from a substance arranged on said carriage, a chain driven by said carriage, and operative connections between said chain and said slice receiver for moving said slice receiver along its path of movement as said carriage reciprocates at a greater rate of speed 110 than said carriage.

14. In a slicing machine, the combination with a rotating knife, of gearing for rotating said knife, a reciprocating table movable past the cutting edge of said knife, said table having gear teeth thereon, means for driving said table from the gearing for rotating said knife, a gear meshing with said gear teeth and driven thereby as said table reciprocates, a slice receiver movable in a path parallel to the cutting plane of said knife and on the side thereof opposite to said table, and means driven from said gear for driving said slice receiver along its path of movement and at a speed which is greater than the speed of movement of said table.

15. In a slicing machine, the combination with a rotating knife, of gearing for rotating said knife, a reciprocating table movable past the cutting edge of said knife, said table having gear teeth thereon, means for driving said table from the gearing for rotating said knife, a gear meshing with said gear teeth and driven thereby as said table reciprocates, a slice receiver movable in a path parallel to the cutting plane of 145

said knife and on the side thereof opposite to said table, and means driven from said gear for driving said slice receiver along its path of movement and at a speed different than the speed of movement of the table.

16. In a slicing machine, the combination with a slicing knife, of a substance supporting table having a substantially horizontal substance supporting surface mounted for movement past said knife on one side thereof, of a slice receiver mounted adjacent the end of said table which lies adjacent the cutting plane of said knife, a slice deflector for deflecting slices

as they are cut from a substance on said table broad side down onto the receiving surface on said receiver, means for moving said slice receiver in a substantially rectilinear path extending in a direction substantially parallel to the path of movement of said substance support, the upper surface of said slice receiver being relatively flat and being arranged at an inclination to the horizontal and having the edge thereof adjacent the cutting plane of said knife below the substance supporting surface of said substance support.
